CLAIM

The ornamental design for a speaker enclosure for a motorcycle saddlebag, as shown and described.

DESCRIPTION

FIG. 1 is a back-side perspective view of a speaker enclosure for a motorcycle saddlebag showing our new design;

FIG. 2 is a front-side prospective view thereof;

FIG. 3 is a back side elevation view thereof;

FIG. 4 is a front side elevation view thereof;

FIG. 5 is a left end elevation view thereof;

FIG. 6 is a right end elevation view thereof;

FIG. 7 is a top plan view thereof; and,

FIG. 8 is a bottom plan view thereof.

The broken lines showing portions of the speaker enclosure for a motorcycle saddlebag form no part of the claimed design.

1 Claim, 6 Drawing Sheets(56)
